SINGLE-FACED SLIDING DOORS

Frederick H. Blake, P.O. Box 14, Medina, Wash.

Filed Oct. 1, 1956, Ser. No. 613,056

3 Claims. (Cl. 20—19)

This present invention relates to the general art of sliding doors, and more particularly to a sliding door that is intended to provide a lightweight inexpensive door by the expedient of employing only one sheet of plywood, and that on the showing side of the door, and having the panel stiffened by stiffening members of wood which, in turn, are reinforced with embedded metal strips.

In order to build acceptable housing up to the standards set by the Federal Housing Administration and still keep the cost of the same within a realistic figure that can be amortized by the average young couple, the various builders throughout the country are making every effort to give a good building, but with savings made at any point where the saving will not materially affect the livability of the residence. In the average home there are many door openings, such as closets and the like which, if provided with conventional doors and door framing, add a great deal to the overall cost of a house. As a result, a wide variety of arrangements have been provided to make less expensive closures for such openings, and these have been made out of a wide range of materials and of designs ranging from accordion or folding type to the cheapest expedient of merely placing curtains over the openings.

In my present invention I have provided an economical construction that, from the outward appearance and for all practical purposes, provides a solid door, or preferably a pair of doors, which have all the desirable characteristics of the double panel plywood doors without their attendant weight and cost. In sliding doors it is very desirable to have a door that will not rattle and which will not warp. These conditions could not be fulfilled by the lightweight framed panel door of the general style that has been made for residence doors and stores. The next step was to use sheets of plywood in which the fine veneered woods could be employed and to use two panels, one on the front and one on the back. This arrangement of course called for considerable framing and spacing members which were disposed between the two panels in order to hold them in place.

For many closet openings, for instance, it is unnecessary to provide the interior panel, because it is never seen, and otherwise serves only the purpose of stiffening the door so that it will not warp an excessive amount. With my present arrangement I am able to discard the inner panel, which of course is the full size of the door, and on a double door closure for a clothes closet, for instance, this effects a very appreciable saving.

A still further saving is made in the framing and reinforcing strips which now have only one purpose, and that is to give front and edge finished appearance, as only the front and certain edges can be observed. With my plan it is possible to employ marginal framing of lightweight material relatively and to employ diagonal bracing, again of lightweight material. It has been found that to double the size, for instance, of the framing and bracing members still does not provide a non-warping door where only one panel is employed. I therefore have devised a plan for metal reinforcing the framing and bracing members, and this is achieved by inserting strips of steel which present their edges to the panel or front plane of the door, so that maximum resistance is pro-

2

vided against warping, and it has proven very satisfactory.

The principal object of my present invention therefore is to provide a reinforced single-faced sliding door for single entrance spaces, such as clothes closets and the like.

5 A further object of my present invention is to provide a single-faced sliding door having marginal framing and diagonal bracing, which framing and bracing are reinforced by metal strips that are embedded in the framing materials so as to present the greatest resistance to the warping of the door structure.

A further object of my present invention is to provide guide means for the bottoms of the doors, which engage the doors at one point only, to the end that little, if any, obstruction is offered the housewife when she desires to 15 sweep or vacuum the closet floors.

A further object of my present invention is to employ unique guide means and door-supporting means made of plastic materials, to the end that a noiseless operation is provided for the doors.

20 Further objects, advantages and capabilities will be apparent from the description and disclosure in the drawings, or may be comprehended or are inherent in the device.

In the drawings:

25 Figure 1 is a perspective view showing the back side of two sliding doors made after the teachings of this present invention.

Figure 2 is an enlarged perspective view, partly in 30 section, illustrating the positioning of the steel reinforcing members and the manner in which the bottoms of the doors are held in place against lateral swaying.

Figures 3, 4, 5 and 6 are fragmentary cross-sectional views taken along similarly numbered lines of Figure 1.

35 Figure 7 is a perspective view illustrating the overhead suspension arrangement employed with my doors.

Referring more particularly to the disclosure in the drawings, the numeral 10 designates the facing material for my doors. This is normally of plywood, in order that a lightweight compact door be obtained and also 40 that fullest advantage can be taken of the wide range of imported and domestic decorative woods which are readily obtainable in plywood form, as they cost only slightly in excess of the domestic fir. The plywood panel 10, which provides the face of the door, is normally made 45 three to four feet wide and easily about seven feet high, and thus the panels cut to advantage. As the plywood facing is normally relatively light, in the order of $\frac{1}{4}$ " stock, it must rely upon marginal framing and bracing in order to have sufficient resistance to warping, to make 50 it a practical expedient.

In my present doors I find it desirable to employ top and bottom frame members as 12 and 14 of appreciable weight and then to connect these with vertical marginal framing members 16 and 18. These members, under ideal 55 conditions, give sufficiently rigidity to the margins to hold the panel 10 in a single plane. However, it is very necessary that there be no drumming effect or any tendency to push in the center of the panel. Consequently 60 it has been found desirable to provide the diagonal bracing members as 20 and 22. These members give greatly increased rigidity and again, under ideal conditions of uniform humidity, they would be quite satisfactory in use. Experience has proven, however, that humidity is 65 constantly changing in the average residence and, when this change of moisture content in the ambient air has a chance to permeate the wood, then we get warping not only in panel 10 but in the relatively light marginal and diagonal members.

70 It naturally follows that, if the marginal framing and the diagonal bracing members are reinforced so that they will not warp under conditions of changing humidity,

use and strain, then panel 10 would be held to a true plane and the appearance and utility of the door, of course, would be greatly enhanced. It has been found that, if steel bars or strips, having a thickness less than $\frac{1}{2}$ the thickness of the sheet material forming the door facing, are firmly embedded in saw cuts or milled kerfs in the structural members, the metal bracing, when it is at right angles to the plane of panel 10, will definitely hold the various members in their original positions. As a matter of expedience and for appearances, it is preferred that the metal reinforcing members 30 be embedded in the framing or bracing members on that face which is employed against the plywood, after the showing of Figures 3, 4 and 5. When so employed, the metal reinforcement is entirely hidden from view, and also there is a good depth of wood above the metal strip, as viewed throughout the figures, so that there is no danger of cracking or checking as the result of this metal reinforcement.

In Figure 6 I have illustrated the one exception to the interior placement of the metal reinforcing strip, and that occurs in the diagonal bracing members 20 and has been found desirable where the bracing members cross, as at 35, to employ the reinforcing steel in one piece for the whole length of these diagonal members. Consequently one or the other of the diagonals must have the metal reinforcement member 33 inlet from the exposed face, after the showing of Figure 6, in order that it may cross the metal reinforcement of member 22. If the metal strips 30 and 33 embedded, respectively, in diagonal bracing members 22 and 20 are each one-half of the depth of these members, then they will meet at the intersection 35, but without interference, and no strength is lost as would be occasioned if the metal strips were cut at this point.

The upper margins of the doors are held in position and disposed for movement across the door opening by the trackage and rollers illustrated in Figures 1, 7 and 8, wherein rollers 42, preferably formed of plastic, are journaled on brackets 44, which brackets are fixedly secured to the door or doors 10. A desirable form of V-shaped trackage 46 is provided to support and direct the cams of rollers 42. This track is suitably supported from the framing of the door opening.

This arrangement, however, leaves the bottoms of the doors free to swing, and this is quite typical of many closet installations where it is not desirable, because of the expense involved, to have the sliding doors go into pockets in the walls, such as is occasioned by the use of the sliding doors as closures for rooms that are occupied on both sides of the doors. A very satisfactory means for holding the doors from swaying and still an item that will not interfere with the housewife in sweeping the floor or vacuuming the rugs of the closets, is to provide a double channel member, as illustrated in Figures 1 and 2. This channel member is best formed of plastic of the type that has some characteristic that lends it to polishing. Plastics of the order of "nylon" or "Teflon" are good examples of this type.

The member 50 provides one or two channels 52 in accordance with whether two doors or only one door is employed. The outer wall as 54 engages the outer face of the door and the bottom framing member 14. If two doors are employed as shown in Figures 1 and 2, then the central guide member as 56 is the dividing line between the two channels 52 and it also provides for a slight spacing of the doors so that they will not actually rub against each other in sliding. It is because of this oversliding arrangement that it is so desirable to have doors that will not warp, and this present arrangement is positive assurance of smooth operation of doors under these circumstances. The advantage of a guide means after the showing of guide member 50 is that the side margins of the door or door framing are engaged, in contradistinction to the more common method formerly used, in which a post arrangement was employed hav-

ing a key-like member which requires that the bottom of the door be grooved clear across the base of the door to provide a guideway. Such arrangements were never entirely satisfactory, and the present arrangement is much superior. The relatively short piece of plastic material that shows at the bottom of the door is very inconspicuous, especially as it is possible to make the plastic materials of colors that will harmonize well with the different types of wood finishes.

It is believed that it will be clearly apparent from the above description and the disclosure in the drawings that the invention comprehends a novel construction of sliding doors.

Having thus disclosed the invention, I claim:

1. A lightweight single-faced sliding door, comprising: a facing formed as a single sheet from a single sheet of lightweight plywood; peripheral frame members, secured only to said facing, having a top member, a bottom member and vertical marginal members; diagonally disposed bracing members within the peripheral frame; strip metal reinforcing members, having a thickness less than $\frac{1}{2}$ the thickness of said sheet of plywood, embedded in kerfs in said frame and diagonal members; the metal reinforcing members disposed in one of the diagonal members adjacent the facing and in the coating diagonal members disposed in the edge farthest removed from said facing in order that the reinforcing members may cross each other; said reinforcing members disposed with the plane of the reinforcing members at right angles to the said facing; said reinforcing members extending the full length of said frame and diagonal members; and means for slidably supporting said door.
2. A lightweight single-faced sliding door, comprising: a facing formed as a single lightweight sheet from a plurality of wood parts; peripheral frame members secured only to said facing having a top member, a bottom member and vertical marginal members; diagonally disposed bracing members within the peripheral frame; strip metal reinforcing members, having a thickness less than $\frac{1}{2}$ the thickness of said sheet, embedded in kerfs in said frame and diagonal members the depth of said reinforcing members disposed with the plane of the reinforcing members at right angles to the said facing; and door hangers and trackage for operatively supporting said door.
3. A lightweight single-faced sliding door comprising: a facing formed as a single lightweight sheet from a plurality of wood parts; peripheral frame members secured to said facing having a top member, a bottom member and vertical marginal members; diagonally disposed bracing members within the peripheral frame; strip metal reinforcing members, having a thickness less than $\frac{1}{2}$ the thickness of said sheet, embedded in said diagonal members and extending substantially half-way through the depth of the same; said reinforcing members disposed in kerfs and with the plane of the reinforcing members at right angles to the said facing; each of said reinforcing members extending substantially the full length of the diagonals of said door and crossing at the intersection of the diagonal members; means for the operatively supporting of said door; and guide means for said door to insure its positioning with respect to its plane of travel.
